ORGANIC COMPOUNDS AND PROCESS

Raymond L. Pederson, Kalamazoo Township, Kalamazoo County, Mich., assignor to The Upjohn Company, Kalamazoo, Mich., a corporation of Michigan

No Drawing. Application October 10, 1955
Serial No. 539,671

21 Claims. (Cl. 260—397.47)

The present invention relates to a novel process for the production of 17-ketosteroids and is more particularly concerned with a process of producing 17-ketosteroids selected from the group consisting of 3-oxygenated 17-ketoandrostanes and 17-ketoetiocholanes, the intermediate 20-halobisnorcholan-22-als selected from the group consisting of 3-ketobisnor-20-halo-4-cholen-22-als; 3-ketobisnor-20-halochohan-22-als; 3-ketoallobisnor-20-halochohan-22-als; 3-hydroxybisnor-20-halochohan-22-als and 3-acyloxybisnor-20-halochohan-22-als; 3-hydroxyallobisnor-20-halochohan-22-als and 3-acyloxyallobisnor-20-halochohan-22-als; 3-hydroxybisnor-20-halo-5-cholen-22-als and 3-acyloxybisnor-20-halo-5-cholen-22-als; 3,11-diketobisnor-20-halo-4-cholen-22-als; 3-ketobisnor-11 α -hydroxy-20-halo-4-cholen-22-als; 3-ketobisnor-11 β -hydroxy-20-halo-4-cholen-22-als and 3,6-diketobisnor-20-halochohan-22-als, wherein the halogen atom has an atomic weight of 34 to 81, inclusive, and wherein the acyl group is of an organic carboxylic acid containing from one to eight carbon atoms, inclusive; 17(20)-bisnorchohan-22-als, and a process of production thereof.

The novel process and the new intermediates II and III may be illustratively represented by the following equations:

wherein n and n' are whole numbers from one to two inclusive and wherein X is a halogen atom having an atomic weight between 34 and 81.

The term "17-ketosteroid of the androstane series" is used generally throughout this description of the invention and refers to those compounds of the androstane series having a 17-keto group with or without double bonds in positions such as positions 1, 4, 5(6), and the like. According to the present invention these compounds are preferably oxygenated in the 3-position that

is substituted in the three position by hydroxy, acyloxy, wherein the acyl group is of an organic carboxylic acid containing from one to eight carbon atoms and preferably from a hydrocarbon carboxylic acid containing from 5 one to eight carbon atoms, inclusive, or keto groups. In addition to a 3-oxygenated group, the 17-ketosteroids of the androstane series may be oxygenated in other positions especially on the 11-carbon atom.

Similarly, the term 17-ketosteroids of the etiocholane series is used to refer to those compounds of the etiocholane series having a 17-keto group. According to the invention, these compounds may also have double bonds in positions 1, 6(7), and the like and may be oxygenated in position 3, having a 3-hydroxy, acyloxy, defined as above, or keto group. In addition the 17-ketosteroid of the etiocholane series can be substituted by keto groups especially in positions 6, 11, and the like.

The process of the present invention comprises: treating a 22-(N-tertiaryamino)-bisnorcholane (I), dissolved 20 in an organic solvent, with halogen, such as bromine and chlorine or with a halogen releasing agent such as an N-haloacetyl amide in acid solution, to give the corresponding 20-halo-bisnorcholane-22-al (II), dehydrohalogenating the 20-halo-bisnorcholane-22-al by heating with 25 a tertiary amine, such as N-methylpiperidine, pyridine, triethylamine, collidine, or the like, to obtain a 17(20)-bisnorcholane-22-al (III) and ozonolizing the 17(20)-bisnorcholane-22-al to obtain the corresponding 17-ketosteroid of the androstane series or of the etiocholane 30 series (IV).

It is an object of the present invention to provide a method for the production of 17-ketosteroids of the androstane and etiocholane series from the corresponding bisnorcholane enamines, produced from readily available bisnorcholane aldehydes. It is another object of the instant invention to produce useful steroid intermediates belonging to the class of 20-halo-bisnorcholane-22-als selected from the group consisting of the 3-ketobisnor-20-halo-4-cholen-22-als, 3-ketobisnor-20-halochohan-22-als, 3-ketoallobisnor-20-halochohan-22-als, the 3-hydroxy- and 3-acyloxybisnor-20-halochohan-22-als, 3-hydroxy- and 3-acyloxyallobisnor-20-halochohan-22-als, the 6- and 11-hydroxy, acyloxy and keto derivatives thereof, wherein 40 the acyl group is of an organic carboxylic acid containing from one to eight carbon atoms, inclusive, and preferably of a hydrocarbon carboxylic acid containing from one to eight carbon atoms, and wherein the halogen has an atomic weight between 34 and 81. It is another 45 object of the instant invention to provide a process for the production of the dehydrohalo derivatives of the foregoing compounds, the new class of 17(20)-bisnorcholane-22-als, such as especially 3-ketobisnor-4,17(20)-choladien-22-als, 3-ketobisnor-17(20)-cholen-22-als, 3-hydroxy- and 3-acyloxybisnor-17(20)-cholen-22-als, 3-hydroxy- and 3-acyloxybisnor-5,17(20)-choladien-22-als wherein the acyl group is defined as above, and the 6- and 11-hydroxy, acyloxy and keto derivatives thereof. Other objects of the present invention will be apparent 55 to those skilled in the art to which this invention pertains.

The intermediates and the process of the present invention are useful for the production of physiologically active compounds. Thus from the 22-enamines of 3-ketobisnor-4-cholen-22-al there are obtained in sequence (cf. Examples 1-3) 3-ketobisnor-20-halo-4-cholen-22-als, 3-ketobisnor-4,17(20)-choladien-22-als, and finally 4-androstene-3,17-dione possessing androgenic properties and being an intermediate in the production of testosterone. 3,11-diketobisnor-4-cholen-22-al 22-enamine by 65 this process yields adrenosterone; 3-keto-11 α -hydroxy and 3-keto-11 β -hydroxybisnor-4-cholen-22-al 22-en-

amines which yield 11α -hydroxy- and 11β -hydroxy-4-androstene-3,17-dione which have androgenic and anabolic activity and are oxidizable by chromic acid in acetic acid to adrenosterone; 3α - or 3β -hydroxybisnorcholan-22-al 22-enamine give anesthetically active 3α - or 3β -hydroxyetiocholan-17-one; $3,11$ -diketobisnorcholan-22-al 22-enamine gives etiocholane-3,11,20-trione (general anesthetic activity); 3 -hydroxy- or 3 -acyloxy-6-ketobisnorcholan-22-al 22-enamine provide the corresponding 3 -hydroxyetiocholane-6,17-dione and 3 -esters thereof which are oxidized (in case of a 3 -ester, after hydrolysis) to the corresponding etiocholane-3,6,17-trione, brominated to 4 -bromoetiocholane-3,6,17-trione and dehydrobrominated to give 4 -androstene-3,6,17-trione of estrogenic activity. Similarly the etiocholane-3,6,17-trione from which 4 -androstene-3,6,17-trione is prepared may also be prepared from $3,6$ -diketobisnorcholan-22-al 22-enamine. $3,11$ -bisnorallocholan-22-al 22-enamines yield androgenically active androstane-3,11,17-trione.

The starting compounds of the present invention are 22 -(*N*-tertiaryamino)-bisnorcholanes wherein the tertiary amino radical is preferably of the formula:

in which n and n' are whole numbers from one to two, inclusive.

The preferred 22 -(*N*-tertiaryamino)-bisnor- 20 (22)-cholenes are selected from the group consisting of 22 -(*N*-tertiaryamino)-bisnor- $4,20$ (22)-choladien-3-ones, 22 -(*N*-tertiaryamino)-allobisnor- 20 (22)-cholen-3-ones, 3 -hydroxy- and 3 -acyloxy- 22 -(*N*-tertiaryamino)-bisnor- 20 (22)-cholen-3-ones, 3 -hydroxy- and 3 -acyloxy- 22 -(*N*-tertiaryamino)-allobisnor- 20 (22)-cholen-3-ones, 3 -hydroxy- and 3 -acyloxy- 22 -(*N*-tertiaryamino)-bisnor- $5,20$ (22)-choladien, 3 -hydroxy- and 3 -acyloxy- 22 -(*N*-tertiaryamino)-bisnor- $5,20$ (22)-choladien-11-ones, 3 -hydroxy- and 3 -acyloxy- 22 -(*N*-tertiaryamino)-bisnor- $4,20$ (22)-choladien-6-ones, wherein the acyloxy group is of an organic carboxylic acid having from one to eight carbon atoms and wherein the tertiary amino radical is defined as before. Such enamines are prepared by the methods shown by Herr and Heyl, J. Am. Chem. Soc. 74, 3629 (1952) from the corresponding bisnor-cholan-aldehyde. Many of the bisnorcholan aldehydes are known and readily available, while other bisnorcholan aldehydes may be obtained by reduction of the corresponding bisnorcholanic acid as shown in the preparations. Representative starting steroids thus used comprise: the 22 -*N*-piperidyl, 22 -*N*-pyrrolidyl, 22 -*N*-morpholinyl, 22 -*N*-homomorpholinyl enamines of bisnorcholan- 22 -al, 3 -acetoxybisnorcholan- 22 -al, 3 -hydroxybisnorcholan- 22 -al, 3 -benzoyloxybisnorcholan- 22 -al, 3 -methoxybisnorcholan- 22 -al, 3 -ketobisnorcholan- 22 -al, 3 -ketoallobisnorcholan- 22 -al, 3 -ketobisnor- 4 -cholen- 22 -al, 3β -hydroxybisnor- 5 -cholen- 22 -al, 3 -acetoxybisnor- 5 -cholen- 22 -al, $3,11$ -diketobisnor- 4 -cholen- 22 -al, $3,11$ -diketobisnorcholan- 22 -al, 3 -ketoallobisnorcholan- 22 -al, 3 -keto- 11α -hydroxy- and 11β -hydroxybisnor- 4 -cholen- 22 -al, $3,6$ -diketobisnorcholan- 22 -al, 3 -acetoxybisnorallocholan- 22 -al, 3 -ketobisnorallocholan- 22 -al, maleic anhydride adduct of bisnor- $5,7$ -choladien- 22 -al- 3β -ol, and the like.

In carrying out the process of the present invention the selected 22 -*N*-tertiaryaminobisnor- 20 (22)-cholen, preferably dissolved in an organic solvent such as ethyl acetate, carbon tetrachloride, methylene dichloride, ethylene dichloride, chloroform, dioxane, tertiary butyl alcohol, dimethylformamide, methanol, ethanol, acetic acid, and the like, is reacted with the selected halogen dissolved in a similar organic solvent. The temperature of the reaction is between minus eighty degrees and room temperature, up to thirty degrees centigrade. In

the preferred embodiment of the invention a temperature between minus thirty and plus fifteen degrees centigrade is preferred.

With very low temperatures, instead of the 20 -bromobisnorcholan aldehyde, a 20 -bromo- 22 -quaternary ammonium bisnorcholane halide is produced as shown in Example 1A. These quaternary ammonium compounds while stable when solid, melt and are unstable at room temperature. In a solution of an organic solvent such as in ethanol, methylene dichloride, chloroform, carbon tetrachloride solution, and in the presence of water, they split off the quaternary ammonium group and thus are converted to 20 -halobisnorcholan aldehydes.

Instead of using solutions of the free halogen, halogenation can be effected by producing the halogen molecule in situ such as, for example, by allowing to react in the solution of the enamine, an *N*-haloacylamide such as *N*-bromoacetamide, *N*-bromosuccinimide, and *N*-chlorosuccinimide with a dilute acid such as dilute hydrochloric, dilute sulfuric, dilute perchloric, dilute periodic, and other acids. The proportion of halogen or halogen releasing reactant is usually close to the calculated theoretical amount; that is, about a mole of the halogen is used for each mole of enamine. Smaller or larger proportions are operative but no additional advantage is obtained. Upon termination of the reaction, the product is isolated from the reaction mixture by conventional means such as elimination of the excess of inorganic agents by washing with suitable reagents, for example, sodium bisulfite, a dilute basic reagent such as sodium bicarbonate, dilute sodium hydroxide or potassium hydroxide solution and water and thereafter extraction with water-immiscible solvents such as ether, methylene dichloride, chloroform, and the like, evaporation, crystallization, or chromatography as deemed necessary to obtain the 20 -halobisnorcholan compounds.

The dehydrohalogenation of 20 -halobisnorcholan-aldehyde thus produced is accomplished by heating the 20 -halobisnorcholan aldehydes with a tertiary amine such as pyridine, collidine, picoline, triethylamine, isoquinoline or substituted acyl amides such as dimethyl formamide, diethyl formamide, or the like. The preferred and most convenient reagent for carrying out the dehydrohalogenation is pyridine. In the dehydrohalogenation it is advantageous but not necessary to use lithium salts such as lithium chloride or lithium bromide. These salts have an accelerating affect on the dehydrohalogenation. The dehydrohalogenation reaction is usually carried out between about fifty degrees centigrade and the reflux temperature of the selected solvent. With pyridine a temperature between sixty to 100 degrees is preferred. The time of the reaction is not critical and is generally between one-half hour and six hours depending upon the temperature. The thus-obtained products, bisnor- 17 (20)-cholen- 22 -als are isolated by suitable conventional means such as diluting the reaction mixture with water, separating the water layer from the organic layer, washing the organic layer, concentrating the organic layer to leave the bisnor- 17 (20)-cholen- 22 -al as a residue which can be purified in the conventional manner such as recrystallization, washing and extracting and/or chromatography.

The thus-obtained bisnor- 17 (20)-cholen- 22 -als are then subjected to ozonolysis. In the preferred embodiment of the invention the ozonolysis is effected in standard ozonization equipment and at low temperatures such as minus eighty to plus ten degrees centigrade. At the termination of the ozonization procedure the thus-obtained 17 -ketoandrostane or 17 -ketoetiocholane material is separated by conventional means such as by washing the reaction mixture, solvent extraction with water immiscible solvents as mentioned before, recrystallization, and/or chromatography as deemed necessary.

The following examples are illustrative of the process

and products of the present invention but are not to be construed as limiting.

PREPARATION 1

3-acetoxy-22-(N-homomorpholino)-bisnor-5,7,20(22)-cholatrien 5,8-dimethyl maleate adduct

3-acetoxybisnor-5,7-choladien-22-al 5,8-dimethyl maleate adduct was refluxed for a period of six hours in benzene with a solution of homomorpholine [Braun et al., Ber. 54B, 685 (1921)] and para-toluenesulfonic acid. The water formed during the reaction was removed by a water trap connected to the reflux condenser. Thereafter the mixture was condensed under vacuum and the crystals remaining in the reaction flask were repeatedly recrystallized from benzene to give pure 3-acetoxy-22-(N-homomorpholino)-bisnor-5,7,20(22)-cholatrien-5,8-dimethyl maleate adduct.

Otherwise like Preparation 1, by reacting a 3-oxygenated bisnorcholan-22-al with a cyclic amine, such as piperidiné, pyrrolidiné, morpholine, homomorpholine, 2-méthylloxazolidiné, trimethylenimine, or with another secondary amine such as dialkylamine, dicycloalkylamine, alkyl aralkylamine, dialkanoylamine or diaralkylamine other 3-oxygenated-22-(N-tertiaryamino)-bisnor-20(22)-choléne are prepared such as 22-(N-pyrrolidino)-bisnor-4,20(22)-choladien-3-one, 22-(N-homomorpholino)-bisnor-4,20(22)-choladien-3-one, 22-(N-trimethylenimino)-bisnor-4,20(22)-choladien-3-one, 22-(N-tetrahydroisoquinolino)-bisnor-4,20(22)-choladien-3-one, 22-(N-pyrrolidino)-bisnor-5,7,20(22)-cholatrien 5,8-dimethyl maleate adduct, 3-phenylacetoxy-22-(N-morpholino)-bisnor-4,20(22)-choladien, 22-(tetrahydroisoquinoline)-bisnor-20(22)-cholen-3-one, 22-[N-(N-dicyclohexylamino)]-bisnor-3β-methoxy-20(22)-cholen, 22-[N-(N-dodecylamino)]-bisnor-3α-naphthoxy-20(22)-cholen, 3-hydroxy-22-(N-2-méthylloxazolidino)-bisnor-5,20(22)-choladien, 22-(N-pyrrolidino)-bisnor-20(22)-cholen-3-one, 5,8-diethyl maleate adduct of 3-acetoxy-22-[N-(N-diethanolamino)]-bisnor-5,7,20(22)-cholatrien, and the like.

PREPARATION 2

11β-hydroxy-22-(N-piperidyl)-bisnor-4,20(22)-choladien-3-one

A mixture of 3.3 grams of 3,11-diketobisnor-4-cholenic acid (obtained by chromic acid oxidation of 3-ketobisnor-11α,22-dihydroxy-4-cholene, Murray and Peterson U. S. Patent 2,602,769, issued July 8, 1952) and ten milliliters of oxalyl chloride in benzene was maintained at room temperature for sixteen hours in the presence of pyridine. The excess of oxalyl chloride was eliminated by distillation under reduced pressure.

The thus-obtained 3,11-diketobisnor-4-cholenic acid chloride was then reduced to the aldehyde by the method of Weygand et al. [Angew. Chem. 65, 525 (1953)]. For this purpose, the crude (and cooled) 3,11-diketobisnor-4-cholenic acid chloride was dissolved in 100 milliliters of benzene and to this solution was added 4.5 milliliters of methylaniline, a four-fold excess of methylaniline. The mixture was heated for ten minutes on the water bath, cooled and thereafter transferred to a separatory funnel. The cooled benzene solution was washed successively with three five-milliliter portions of water, a fifteen-milliliter portion of five percent hydrochloric acid, a fifteen-milliliter portion of five percent sodium hydroxide solution and five-milliliter portions of water until the wash-water was neutral to phenolphthalein. The benzene solution was then evaporated and the product, 3,11-diketobisnor-4-cholenic acid methylanilide was once recrystallized from methanol and water.

The 3,11-diketobisnor-4-cholenic acid methylanilide thus-obtained, admixed with three milliliters of distilled ethylene glycol, 150 milligrams of para-toluenesulfonic

acid and sixty milliliters of benzene was placed in a reaction flask equipped with a reflux condenser and a water trap. The mixture was heated under reflux with stirring for ten hours. The water which was formed was removed by co-distillation with benzene and collected in the water trap. The reaction mixture was cooled, washed with dilute sodium bicarbonate solution and with water, dried, and evaporated under reduced pressure to give after two recrystallizations from ethyl acetate-Skellysolve B (hexanes), a white crystalline residue 3-ethylene ketal of 3,11-diketobisnor-5-cholenic acid methylanilide.

To a solution of 1.2 grams of lithium aluminum hydride, dissolved in 100 milliliters of anhydrous ether, was added dropwise the thus-obtained 3-ethylene ketal of 3,11-diketobisnor-5-cholenic acid methylanilide dissolved in 35 milliliters of tetrahydrofuran. The resulting mixture was stirred for one-half hour at a temperature of zero to five degrees centigrade, thereafter for one hour at room temperature (about 25 degrees centigrade) after which time it was refluxed for another hour and then cooled and hydrolyzed with fifteen milliliters of water. The organic layer was separated by decantation and the remaining paste was suspended in water and repeatedly extracted with methylene dichloride. The combined ether and methylene dichloride solutions were concentrated to give crystalline 3-ethylene ketal of 3-ketobisnor-11β-hydroxy-5-cholen-22-al.

The thus obtained 3-ethylene ketal of 3-ketobisnor-11β-hydroxy-5-cholen-22-al was then refluxed in a mixture of 100 milliliters of methanol, 25 milliliters of water, and two milliliters of sulfuric acid for a period of two hours. Thereafter the reaction mixture was neutralized with sodium bicarbonate solution and poured into one liter of cracked ice. The thus obtained crystalline material was collected on filter and recrystallized from methanol and Skellysolve B to give pure 3-ketobisnor-11β-hydroxy-4-cholen-22-al.

A mixture of two grams of 3-ketobisnor-11β-hydroxy-4-cholen-22-al, 50 milliliters of thiophene-free benzene and two milliliters of piperidine was placed in a distilling flask equipped with a reflux condenser so arranged that the condensed vapors passed through eight grams of absorbent anhydrous aluminum oxide particles before returning to the reaction zone, and the mixture was heated under reflux for two hours under an atmosphere of nitrogen. The benzene was then removed at subatmospheric pressure and the residue was thoroughly agitated with ten milliliters of methanol. The methanolic extract was then cooled to about four degrees centigrade for a period of four hours, filtered, and the filter cake washed with about one milliliter of cold methanol and dried to obtain 11β-hydroxy-22-(N-piperidyl)-bisnor-4,20(22)-choladien-3-one.

22-(N-piperidyl)-bisnor-4,20(22)-choladien-3,11-dione can be obtained by reducing the 3,11-diketobisnor-4-cholenic acid chloride in the manner shown by Rosenmund, Ber. 51, 585 (1918) with hydrogen in the presence of a palladium barium sulfate catalyst. The thus obtained 3,11-diketobisnor-4-cholen-22-al is reacted with piperidine in the manner shown before to give the 22-(N-piperidyl)-bisnor-4,20(22)-choladine-3,11-dione.

11α-hydroxy-22-(N-piperidyl)-bisnor-4,20(22)-choladien-3-one is obtained by reacting 3,11-diketobisnor-4-cholenic acid chloride with hydrogen in the presence of barium sulfate to obtain 3,11-diketobisnor-4-cholen-22-al, reacting the thus produced 3,11-diketobisnor-4-cholen-22-al with ethylene glycol to obtain the 3,22-di(O,O-dioxyethylene)-11-ketobisnor-4-cholene, reducing the thus obtained ketal with sodium in propanol as shown by Herzog et al., J. Am. Chem. Soc. 75, 270 (1953) to obtain 3,22-di(O,O-dioxyethylene)-11α-hydroxybisnor-4-cholen and hydrolyzing the 3-ketal and the 22-acetal groups with a dilute mineral acid to obtain 3-ketobisnor-11α-hydroxy-4-cholen-22-al which by reaction with piperidine in the

manner shown above produces 11α -hydroxy-22-(N-piperidyl)-bisnor-4,20(22)-choladien-3-one.

Reduction of 3,11-diketobisnor-4-cholen-22-al with hydrogen in the presence of a palladium catalyst on zinc carbonate or palladium in a generally basic medium gives the corresponding 3,11-diketobisnorcholan-22-al which may be converted to the corresponding 22-piperidino, morpholino, tetrahydroisoquinolino, oxazolidino, homomorpholino, pyrrolidino, and the like enamines, by the methods of Heyl and Herr given above.

Similarly other 22-enamines of 3-hydroxy-11-keto or 3,11-dihydroxybisnorcholen-22-als are obtained by reducing the 3-keto position of available 3,11-diketobisnor-4-cholen-22-al or 3-keto-11 α -hydroxy and 3-keto-11 β -hydroxybisnor-4-cholen-22-al 22-enamines with sodium borohydride.

Esterifying such compounds produces the corresponding 3-acyloxy-11-keto and 3,11 α -diacyloxybisnorcholen-22-al 22-enamines. Representative 22-(N-tertiaryamino)-bisnor-20(22)-cholenes thus obtained comprise: 11 β -hydroxy-22-(N-piperidyl)-bisnor-4,20(22)-choladien-3-one, 11 α -hydroxy-22-(N-morpholinyl)-bisnor-4,20(22)-choladien-3-one, 11 α -acetoxy-22-(N-pyrrolidyl)-bisnor-4,20(22)-choladien-3-one, 22-(N-homomorpholino)-bisnor-4,20(22)-choladiene-3,11-dione; 3 α ,11 β -dihydroxy-22-[N-(2-methyloxazolidino)]-bisnor-20(22)-cholene; 3 α ,11 α -dipropionyloxy-22-[N-(N-tetrahydroisoquinolyl)]-bisnor-20(22)-cholene; 3 α -butyryloxy-11 β -hydroxy-22-[N-(N-dibenzylamino)]-bisnor-20(22)-cholene; 3 α -benzoyloxy-22-(N-piperidyl)-bisnor-4,20(22)-choladien-11-one; 3 α -(2-furoyloxy)-22-(N-morpholinyl)-bisnor-20(22)-cholene-11-one; 3 α -nicotinyloxy-22-(N-piperidyl)-bisnor-4,20(22)-choladien-11-one, and the like.

PREPARATION 3

$3\beta,6\beta$ -dihydroxy-22-(N-piperidyl)-bisnor-20(22)-cholene

In the manner shown in Preparation 2, 3-acetoxy-6-ketobisnorcholanic acid, prepared by the manner of Herbert Q. Smith et al., J. Org. Chem. 19, 1628 (1954), when reacted with oxalyl chloride produced the 3-acetoxy-6-ketobisnorcholanic acid chloride. Using the method of Weygand et al. [Angew. Chem. 65, 525 (1953)] to reduce the 3-acetoxy-6-ketobisnorcholanic acid chloride yields the $3\beta,6\beta$ -dihydroxybisnorcholan-22-aldehydes which is reacted as shown in Preparations 1 and 2 by the method of Heyl and Herr with piperidine to give the corresponding $3\beta,6\beta$ -dihydroxy-22-(N-piperidyl)-bisnor-20(22)-cholene.

By treatment of the $3\beta,6\beta$ -dihydroxybisnorcholane aldehyde with acyl chlorides or acyl bromides the corresponding acyloxy esters are obtained such as, for example, the diacetoxyl, dipropionyloxy, dibutyryloxy, di-valeryloxy, dihexanoyloxy, dibenzoyleoxy, disalicyloyloxy, dihemifumarylxyloxy, di-(2-furoyloxy), dinicotinyloxy, and the like. Such $3\beta,6\beta$ -diacyloxybisnorcholan aldehydes can be converted to the corresponding 22-enamines by the aforementioned methods.

Oxidation of $3\beta,6\beta$ -dihydroxybisnorcholan aldehyde 22-enamines by Oppenauer oxidation produces the corresponding 22-(N-tertiaryamino)-bisnor-20(22)-cholene-3,6-diones. Reduction of the 3- and 6-diketo groups with sodium borohydride produces the corresponding 3 α ,6 α -dihydroxy-22-(N-tertiaryamino)-bisnor-20(22)-cholenes.

In the manner shown in Preparation 3, the other 3,6-dioxygenated 22-(N-tertiaryamino)-bisnor-20(22)-cholenes are produced such as illustratively: $3\beta,6\beta$ -dihydroxy-22-(N-morpholinyl)-bisnor-20(22)-cholene, $3\beta,6\beta$ -diacetoxyl-22-(N-pyrrolidyl)-bisnor-20(22)-cholene, $3\beta,6\beta$ -dipropionyloxy-22-(N-piperidyl)-bisnor-20(22)-cholene, $3\beta,6\beta$ -dibutyryloxy-22-(N-piperidyl)-bisnor-20(22)-cholene, $3\beta,6\beta$ -dibenzoyloxy-22-(N-piperidyl)-bisnor-20(22)-cholene, $3\beta,6\beta$ -diphenylacetoxyl-22-(N-piperidyl)-bisnor-20(22)-cholene, $3\beta,6\beta$ -dicinnamylxyloxy-22-(N-piperidyl)-bisnor-20(22)-cholene, $3\alpha,6\alpha$ -ditoluyloxy-22-(N-piperidyl)-

bisnor-20(22)-cholene, $3\alpha,6\alpha$ -dinicotinyloxy-22-(N-piperidyl)-bisnor-20(22)-cholene, $3\alpha,6\alpha$ -di-(2-furoyloxy)-22-(N-piperidyl)-bisnor-20(22)-cholene, $3\alpha,6\alpha$ -di-chloroacetoxyl-22-(N-piperidyl)-bisnor-20(22)-cholene-3,6-dione, 22-(N-morpholinyl)-bisnor-20(22)-cholene-3,6-dione, 22-(N-piperidyl)-bisnor-20(22)-cholene-3,6-dione, 22-(N-homomorpholinyl)-bisnor-20(22)-cholene-3,6-dione, 22-(N-tetraisoquinolinyl)-bisnor-20(22)-cholene-3,6-dione, 22-(N-oxazolidinyl)-bisnor-20(22)-cholene-3,6-dione, and the like.

EXAMPLE 1

3-keto-20-bromobisnor-4-cholen-22-al

A solution containing 39.6 grams (0.1 mole) of 22-(N-piperidyl)-bisnor-4,20(22)-choladien-3-one, dissolved in 1200 milliliters of methylene chloride was cooled to a temperature of about minus 25 degrees centigrade. To this solution was added sixteen grams of bromine, dissolved in 100 milliliters of carbon tetrachloride, over a period of twenty minutes while stirring. The reaction mixture was thereupon warmed to about zero degrees centigrade and 300 milliliters of cold water was added and the mixture was stirred for a period of an additional three hours. The organic layer was separated, washed twice with 300 milliliters of water, dried over anhydrous sodium sulfate, filtered and concentrated at reduced pressure. The thus-obtained residue weighed 40.1 grams (theory=40.7 grams) and was mainly 3-keto-20-bromobisnor-4-cholen-22-al of melting point 95 to 110. This material was recrystallized twice from methylene chloride-Skellysolve B hexanes to give pure 3-keto-20-bromobisnor-4-cholen-22-al of melting point 124 to 126 degrees centigrade.

Analysis.—Calcd. for $C_{22}H_{31}BrO_2$: C, 64.86; H, 7.67; Br, 19.62. Found: C, 64.90; H, 7.58; Br, 19.69.

Ultraviolet absorption max. is at 241.5 mu, $k=42.56$

$E_{max}^{ethanol}$ 17,350

EXAMPLE 1A

22-(N-piperidyl)-bisnor-4,20(22)-choladien-3-one dibromide

A suspension of 11.87 grams of 22-(N-piperidyl)-bisnor-4,20(22)-choladien-3-one, dissolved in 300 milliliters of petroleum ether, was cooled to a temperature of about 45 minus 78 degrees centigrade. A solution of 4.80 grams of bromine, dissolved in fifty milliliters of methylene dichloride, was added dropwise under stirring over a period of about thirty minutes. Thereafter the mixture was concentrated to dryness in vacuo, leaving 16.40 grams of 22-(N-piperidyl)-bisnor-4,20(22)-choladien-3-one dibromide.

Analysis.—Calcd. for $C_{27}H_{41}Br_2NO$: Br, 28.70. Found: Br, 29.23.

EXAMPLE 1B

3-keto-20-bromobisnor-4-cholen-22-al from 22-(N-piperidyl)-bisnor-4,20(22)-choladien-3-one dibromide

A solution of 11.11 grams (20 millimoles) of 22-(N-piperidyl)-bisnor-4,20(22)-choladien-3-one dibromide, dissolved in fifty milliliters of 95 percent ethanol, was allowed to stand at room temperature (twenty to thirty degrees centigrade) for a period of three hours. Thereafter the dark solution was diluted with 100 milliliters of methylene chloride and was washed with six 25-milliliter portions of water. The solution was then dried with ten grams of anhydrous sodium sulfate and concentrated to dryness in vacuo, leaving 6.90 grams of residue. Recrystallization from acetone yielded 4.35 grams (53.3 percent) of 3-keto-20-bromobisnor-4-cholen-22-al of melting point 126 to 129.

EXAMPLE 2

3-ketobisnor-4,17-choladien-22-al

A solution of 40.7 grams (0.1 mole) of 3-keto-20-

bromobisnor-4-cholen-22-al in 200 milliliters of pyridine was heated to a temperature of about seventy degrees centigrade for approximately one hour and thereafter on the steam bath for an additional hour. The solution was then concentrated in vacuo using continuous stirring, until a thick slurry was obtained. The slurry was dissolved in 200 milliliters of methylene chloride, washed twice with water, twice with dilute acid, once with aqueous sodium hydroxide and with water. After drying over anhydrous sodium sulfate, ten grams of Florisil magnesium silicate was added and the mixture was agitated for a period of ten minutes. After filtration and concentration of the filtrate, 30.6 grams of crude 3-ketobisnor-4,17-choladien-22-al was obtained. Chromatography over Florisil and evaporation of petroleum ether-acetone eluant gave fractions melting at 136 to 149 degrees centigrade. These fractions when recrystallized from acetone had a melting point of 139 to 141.

Analysis.—Calcd. for $C_{22}H_{30}O_2$: C, 80.93; H, 9.26. Found: C, 80.87; H, 9.23.

EXAMPLE 3

Ozonolysis of 3 - ketobisnor - 4,17 - choladien - 22 - al to give 4-androstene-3,17-dione

A solution containing 1.42 grams (4.36 millimoles) of 3-ketobisnor - 4,17(20) - choladien - 22 - al, 100 milliliters of ethyl acetate, 100 milliliters of methylene chloride and two milliliters of pyridine was placed in a tubular ozonization flask equipped with sparger and cooled to zero degrees centigrade. A stream of ozone containing 0.22 millimole of ozone per minute was used, the ozonization time being 22 minutes. The total amount of ozone as consumed was 4.8 millimoles. Thereafter the contents of the ozonization flask were transferred to a round bottom flask and twenty milliliters of water was added. The mixture was warmed to reflux for a period of one and one-half hours. Thereupon the mixture was cooled, the layers were separated and the organic layer was washed with water. The water layer yielded pyruvic aldehyde, while the organic layer after careful evaporation of the solvent yielded 0.75 gram of residue which was chromatographed over 75 grams of Florisil to give 0.28 gram of 4-androstene-3,17-dione of melting point 171 to 172 degrees centigrade.

A preferred and generally used method is the decomposition of the ozonide by zinc and acetic acid.

EXAMPLE 4

3 α -acetoxy-20-bromobisnorcholan-22-al

A solution containing 3.14 grams (7.1 millimoles) of 3 α -acetoxy-22-(N-piperidyl)-bisnor-20(22)-cholene in 200 milliliters of ethyl acetate was cooled to about eight degrees centigrade. To this solution was added under stirring 12.7 milliliters of a bromine solution in carbon tetrachloride containing a total of 6.4 millimoles of bromine. The bromine solution was added slowly and the addition was continued until the bromine color persisted for one minute. In this manner a precipitate was formed which was removed by filtration. The filtrate was washed with water and dried over sodium sulfate. Evaporation of the solvent at reduced pressure yielded 3.07 grams of 3 α - acetoxy - 20 - bromobisnorcholan - 22 - al. Recrystallization from acetone gave a pure 3 α -acetoxy-20-bromobisnorcholan-22-al of melting point 131 to 132 degrees centigrade.

Analysis.—Calcd. for $C_{24}H_{32}BrO_3$: C, 63.56; H, 8.22; Br, 17.62. Found: C, 63.65; H, 8.13; Br, 16.97.

Otherwise like Example 4, other 3 α - and 3 β -acyloxy-22-(N-tertiaryamino)-bisnor-20(22)-cholene wherein the tertiaryamino radical and the acyloxy group are defined as above may be brominated to give the corresponding 3 α - acyloxy-20-bromobisnorcholan-22-als. Representative of such compounds are the 3 α - and 3 β -acyloxybisnor-20-bromocholan-22-als wherein the acyloxy group is formyl-

oxy, propionyloxy, butyryloxy, isobutyryloxy, valeryloxy, isovaleryloxy, hexanoyloxy, heptanoyloxy, octanoyloxy, benzoxyloxy, (β - cyclopentylpropionyloxy), dimethylacetoxyl, trimethylacetoxyl, phenylacetoxyl, toluylacetoxyl, anisoyloxy, gallyloxy, salicyloyloxy, cinnamylacetoxyl, hemisuccinylacetoxyl, hemitartraryloxy, dihydrogencitryloxy, maleylacetoxyl, hemifumarylacetoxyl, crotonylacetoxyl, acryloyloxy, β - methylcrotonylacetoxyl, cyclohexanecarbonyloxy, dichloroacetoxyl, trichloroacetoxyl, bromoacetoxyl, hemiquinolinoyloxy, nicotinoyloxy, piperonyloxy, 2 - furoyloxy, thioglycollyloxy, para-chlorobenzoyloxy, para-bromobenzoyloxy, meta-nitrobenzoyloxy, 3,5-dinitrobenzoyloxy, benzenesulfonyloxy, para-chlorobenzenesulfonyloxy, para-toluenesulfonyloxy, para-nitrobenzenesulfonyloxy, 3,5-dinitrobenzenesulfonyloxy, benzenephosphonyloxy, and the like.

EXAMPLE 5

3 α -acetoxybisnor-17(20)-cholen-22-al

A solution of 4.53 grams (ten millimoles) of 3 α -acetoxy - 20 - bromobisnorcholan - 22 - al, dissolved in 25 milliliters of pyridine, was heated for a period of two hours on a steam bath. Thereafter the mixture was concentrated under reduced pressure to a solid residue. The residue was dissolved in 100 milliliters of ether and fifty milliliters of water. After separation of the layers the ether solution was washed with 25 milliliters of water, 25 milliliters of ten percent hydrochloric acid solution, and two 25-milliliter portions of water. The solution was thereupon dried over anhydrous sodium sulfate, filtered and concentrated to a volume of about five milliliters. Thereafter the solution was diluted with an equal volume of Skellysolve A hexanes and refrigerated. The first crop of crystals, 2.58 grams, 69.3 percent of melting point 124 to 132 was recrystallized from ether Skellysolve A and gave pure 3 α -acetoxybisnor-17(20)-cholen-22-al of melting point 151 to 154 degrees centigrade.

Analysis.—Calcd. for $C_{24}H_{34}O_3$: C, 77.37; H, 9.74. Found: C, 77.52, 77.38; H, 9.52, 9.21.

EXAMPLE 5A

Dehydrobromination of 3 α -acetoxy-20-bromobisnorcholan-22-al in the presence of lithium chloride to form 3 α -acetoxybisnor-17(20)-cholen-22-al

A solution of 4.53 grams (ten millimoles) of 3 α -acetoxy-20-bromobisnorcholan-22-al and 1.27 grams (30 millimoles) of anhydrous lithium chloride in 12.5 milliliters of dimethylformamide was heated for a period of two hours in a nitrogen atmosphere on a steam bath. The solution was diluted with 125 milliliters of water and the gummy solid which precipitated was triturated with several portions of water. Thereafter the residue was dissolved in 100 milliliters of ether, the solution washed with four 25-milliliter portions of water, dried with five grams of anhydrous sodium sulfate, and concentrated to about five milliliters of volume. This solution was thereupon diluted with five milliliters of Skellysolve A hexane hydrocarbons and refrigerated. A crop of 2.43 grams (65.2 percent) of 3 α -acetoxybisnor-17(20)-cholen-22-al was obtained which could be recrystallized from Skellysolve ether mixtures to give the pure 3 α -acetoxybisnor-17(20)-cholen-22-al.

EXAMPLE 5B

Dehydrobromination of 3 α -acetoxy-20-bromobisnorcholan-22-al with semicarbazide hydrochloride to give 3 α -acetoxybisnor-17(20)-cholen-22-al

To a solution of 2.23 grams of semicarbazide hydrochloride and 1.64 grams of anhydrous sodium acetate, dissolved in ten milliliters of water, was added 4.53 grams of 3 α -acetoxy-20-bromobisnorcholan-22-al in fifty milliliters of dioxane in a nitrogen atmosphere. The mixture was stirred and heated at 45 degrees for a period of twenty minutes. After the original yellow solution became colorless, five grams of pyruvic acid was added. The mixture thereupon was heated to 65 degrees centigrade for a

11

period of two hours. The reaction mixture was then concentrated to a volume of ten milliliters at reduced pressure. The thus obtained syrupy liquid was shaken with 100 milliliters of water and the mixture was extracted with 350-milliliter portions of ether. The extracts were washed with 25 milliliters of water, two 25-milliliter portions of ice cold ten percent sodium hydroxide solution, 25 milliliters of ten percent hydrochloric acid solution and two 25-milliliter portions of water. The yellow ether solution was dried with five grams of sodium sulfate, filtered and concentrated to five milliliters. Dilution with five milliliters of Skellysolve A pentane hydrocarbons and refrigeration yielded 0.45 gram of crystals of melting point 140 to 148 degrees centigrade which was purified by recrystallization as shown in Example 5.

The resinous residue (3.06 grams) contained the corresponding 3-hydroxy compound resulting from hydrolysis.

Otherwise like Examples 5, 5A and 5B, 3 α -hydroxybisor-20-bromocholen-22-al or esters thereof such as 3 α - or 3 β -formate, propionate, butyrate, isobutyrate, valerate, isovalerate, hexanoate, heptanoate, octanoate, benzoate, phenylacetate, anisate, toluate, cinnamate, chloro- and bromoacetate, trichloroacetate, hemisuccinate, hemitartrate, hemimaleate, dihydrogen citrate, can be dehydrobrominated with a tertiary amine such as pyridine, collidine, dimethyl aniline, trimethylamine and other tertiary amines or with dimethylformamide in the presence of a lithium salt such as lithium chloride, lithium bromide, or with semicarbazide and pyruvic acid to give the corresponding 3-hydroxy- or 3-acyloxybisor-17(20)-cholen-22-al.

EXAMPLE 6

3 α -acetoxyetiocholan-17-one

In the manner given in Example 3, substituting for 3-ketobisor-4,17-choladien-22-al in the ozonolysis 3 α -acetoxybisor-17(20)-cholen-22-al results in 3 α -acetoxyetiocholan-17-one.

Substituting for the 3-ketobisor-4,17-choladien-22-al in the ozonolysis 3 α - or 3 β -hydroxybisor-17(20)-cholen-22-al or any of the 3 α - or 3 β -esters named in Example 5 such as the propionate, butyrate, hexanoate, heptanoate or other esters of the corresponding 3 α - or 3 β -hydroxybisor-17(20)-cholen-22-als produces the corresponding 3 α - or 3 β -hydroxyetiocholan-17-ones or respectively the corresponding 3 α - or 3 β -acyloxyetiocholan-17-ones, wherein the acyloxy groups are the same as shown in Example 4.

EXAMPLE 7

3 β ,6 β -dihydroxybisor-20-bromocholan-22-al

In the manner given in Example 1, 3 β ,6 β -dihydroxy-22-(N-piperidyl)-bisor-20(22)-cholen, dissolved in ethyl acetate was treated with bromine to give 3 β ,6 β -dihydroxybisor-20-bromocholan-22-al.

EXAMPLE 8

3 β ,6 β -dihydroxybisor-17(20)-cholen-22-al

In the manner given in Example 2, 3 β ,6 β -dihydroxybisor-20-bromocholan-22-al was dehydrobrominated with pyridine to give 3 β ,6 β -dihydroxybisor-17(20)-cholen-22-al.

EXAMPLE 9

3 β ,6 β -dihydroxyetiocholan-17-one

In the manner given in Example 3, ozonolysis 3 β ,6 β -dihydroxybisor-17(20)-cholen-22-al gives 3 β ,6 β -dihydroxyetiocholan-17-one.

In the manner shown in Example 1, substituting 3-keto-22-N-bisnorpiperidyl-4,20(22)-cholen with 3 α ,6 α -dihydroxy-, 3 α ,6 α -diacyloxy-, 3 β ,6 β -diacyloxy-22-(N-piperidino)-bisor-20(22)-cholen or 22-(N-piperidino)-bisor-20(22)-cholen-3,6-dione yields the corresponding 3 α ,6 α -dihydroxybisor-20-bromocholan-22-al, 3 α ,6 α -diacyloxybisor-, 3 β ,6 β -diacyloxybisor-20-bromocholan-22-al or

12

the 3,6-diketobisor-20-bromocholan-22-al, wherein the acyloxy group is defined as AcO, Ac being the acyl radical of an organic carboxylic acid and in the preferred embodiment of the invention of a hydrocarbon carboxylic acid containing from one to eight carbon atoms, inclusive. Such acyloxy groups comprise: formyloxy, propionyloxy, butyryloxy, isobutyryloxy, valeryloxy, isovaleryloxy, hexanoyloxy, heptanoyloxy, octanoyloxy, benzoyloxy, phenylacetoxyl, anisoyloxy, gallyloxy, thioglycollyloxy, chloroacetoxyl, bromoacetoxyl, di- and trichloroacetoxyl, meta- and para-nitrobenzoyloxy, 3,5-dinitrobenzoyloxy, chloro- and bromo-benzoyloxy, para-toluenesulfonyloxy, benzenesulfonyloxy, β -naphthylsulfonyloxy, and the like.

EXAMPLE 10

3-ketoallobisnor-20-chlorocholan-22-al

Treating a solution of 22-(N-morpholinyl)-allobisnor-20(22)-cholen-3-one with a solution of chlorine in carbon tetrachloride cooled to zero degrees centigrade produced a 3-ketoallobisnor-20-chlorocholan-22-al.

EXAMPLE 11

3-ketoallobisnor-17(20)-cholen-22-al

In the same manner as shown in Example 2, 3-ketoallobisnor-20-chlorocholan-22-al was treated with collidine to produce 3-ketoallobisnor-17(20)-cholen-22-al.

EXAMPLE 12

Androstane-3,17-dione

In the same manner as shown in Example 3, ozonizing 3-keto-allobisnor-17(20)-cholen-22-al yields androstane-3,17-dione.

EXAMPLE 13

3,11-diketobisor-20-bromo-4-cholen-22-al

In the same manner as given in Example 1, treating 22-(N-piperidyl)-bisor-4,20(22)-cholen-3,11-dione with a solution of bromine produces 3,11-diketobisor-20-bromo-4-cholen-22-al.

EXAMPLE 14

3,11-diketobisor-4,17(20)-cholen-22-al

In the same manner as shown in Example 2, dehydrobrominating 3,11-diketobisor-20-bromo-4-cholen-22-al with dimethyl formamide in the presence of lithium bromide yielded 3,11-diketobisor-4,17(20)-cholen-22-al.

EXAMPLE 15

4-androstene-3,11,17-trione

Ozonolysis 3,11-diketobisor-4,17(20)-cholen-22-al in the manner shown in Example 3, produced 4-androstene-3,11,17-trione (adrenosterone).

Substituting for the 22-(N-piperidyl)-bisor-4-cholen-3-one of Example 1, 11 α -hydroxy-, 11 β -hydroxy- or 11 α -acyloxy-22-(N-piperidyl)-bisor-4,20(22)-cholen-3-one, the corresponding 3-ketobisor-11 α -hydroxy-, 3-ketobisor-11 β -hydroxy-, or 3-ketobisor-11 α -acyloxy-20-bromo-4-cholen-22-al, wherein the acyloxy group is of an organic carboxylic, preferably of a hydrocarbon carboxylic acid containing from one to eight carbon atoms as listed in Example 4, are obtained.

Substituting for the 3-ketobisor-20-bromo-4-cholen-22-al of Example 2, 3-keto-11 α -hydroxy-, 3-keto-11 β -hydroxy-, or 3-keto-11 α -acyloxy-20-bromobisor-4-cholen-22-al results in the corresponding 3-ketobisor-11 α -hydroxy-, 3-ketobisor-11 β -hydroxy-, or 3-ketobisor-11 α -acyloxy-4,17(20)-cholen-22-al wherein the acyloxy groups are defined as stated hereinbefore.

Ozonolysis of 3-ketobisor-11 α -hydroxy-4,17(20)-cholen-22-al according to the procedure shown in Example 3, produces 11 α -hydroxy-4-androstene-3,17-dione.

Ozonolysis of 3-ketobisor-11 β -hydroxy-4,17(20)-cholen-22-al produces 11 β -hydroxy-4-androstene-3,17-dione.

13

Ozonolysis of 3-ketobisnor-11 α -acyloxy-4,17(20)-choladien-22-al produces the corresponding 11 α -acyloxy-4-androstene-3,17-dione.

EXAMPLE 16

3,11-diketoallobisnor-20-bromocholan-22-al

22-(N-pyrrolidyl)-bisnor-20(22)-cholene-3,11-dione, suspended in tertiary butyl alcohol at room temperature, was admixed under stirring with hydrochloric acid solution until the enamine was completely dissolved. To this solution was added N-bromoacetamide, dissolved in tertiary butyl alcohol. After about one half of the bromoamide had been added the mixture became cloudy. After all the N-bromoacetamide had been added the reaction mixture was stirred for thirty minutes, diluted with 200 milliliters of water containing five grams of sodium bisulfite, cooled to about zero degrees centigrade and thereupon filtered. The precipitate thus obtained was washed by slurring four times with fifty-milliliter portions of water and dried in a vacuum desiccator. This material was recrystallized from ether methylene chloride to give pure white crystals of 3,11-diketoallobisnor-20-bromocholan-22-al.

EXAMPLE 17

3,11-diketoallobisnor-17(20)-cholen-22-al

In the same manner as given in Example 2, 3,11-diketoallobisnor-20-bromocholan-22-al was refluxed in triethanolamine to give 3,11-diketoallobisnor-17(20)-cholen-22-al.

EXAMPLE 18

Androstane-3,11,17-trione

In the same manner as given in Example 3, 3,11-diketoallobisnor-17(20)-cholen-22-al was ozonized to yield androstane-3,11,17-trione.

Substituting for the 22-(N-tertiaryamino)-allobisnor-cholane-3,11-dione the normal compounds, 22-N-pyrrolidylbisnorcholane-3,11-dione, the corresponding normal bisnorcholane bromide, 3,11-diketobisnor-20-bromocholan-22-al is obtained.

Substituting for the allobisnorcholane compound of Example 17, the normal bisnorcholane compound, 3,11-diketobisnor-20-bromocholan-22-al, the corresponding 3,11-diketobisnor-17(20)-cholen-22-al is obtained by dehydrohalogenation as shown in Example 2.

Ozonizing 3,11-diketobisnor-17(20)-cholen-22-al in the manner shown in Example 3, produces etiocholane-3,11,20-trione.

EXAMPLE 19

In the manner given in Example 1, brominating:

(a) 11 α -hydroxy-22-(N-morpholinyl)-bisnor-20(22)-cholen-3-one produces 3-ketobisnor-11 α -hydroxy-20-bromocholan-22-al.

(b) 11 α -acetoxy-22-(N-piperidyl)-bisnor-20(22)-cholen-3-one produces 3-ketobisnor-11 α -acetoxy-20-bromocholan-22-al.

(c) 11 β -hydroxy-22-(N-piperidyl)-bisnor-20(22)-cholen-3-one produces 3-ketobisnor-11 β -hydroxy-20-bromocholan-22-al.

(d) 3 α -acetoxy-22-(N-homomorpholinyl)-bisnor-5,20(22)-choladine produces 3 α -acetoxybisnor-20-bromo-5-cholen-22-al.

(e) 3 α -hydroxy-22-(N-piperidyl)-bisnor-5,20(22)-choladiene produces 3 α -hydroxybisnor-20-bromo-5-cholen-22-al.

(f) 3 β -acetoxy-6-nitro-22-(N-piperidyl)-bisnor-5,20(22)-choladiene produces 3 β -acetoxybisnor-6-nitro-20-bromo-5-cholene.

(g) 3-keto-9,11-oxido-22-(N-pyrrolidyl)-bisnor-5,7,20(22)-cholatrien-5,8-maleic anhydride adduct produces 3-ketobisnor-9(11)-oxido-22-bromo-5,7-choladien-22-al, 5,8-maleic anhydride.

14

(h) 22-[N-(2-methyloxazolidinyl)]-bisnor-4,20(22)-choladien-3,6,11-trione produces 3,6,11-triketobisnor-20-bromo-4-cholen-22-al.

5

EXAMPLE 20

In the same manner as shown in Example 2, dehydrobrominating with a tertiary amine such as N-dimethylaniline, pyridine, collidine, α -, β -, or γ -picoline, tetrahydroisoquinoline, trimethylamine, and the like:

(a) 3-ketobisnor-11 α -hydroxy-20-bromocholan-22-al produces 3-keto-11 α -hydroxybisnor-17(20)-cholen-22-al.

(b) 3-ketobisnor-11 α -acetoxy-20-bromocholan-22-al produces 3-keto-11 α -acetoxybisnor-17(20)-cholen-22-al.

(c) 3-ketobisnor-11 β -hydroxy-20-bromocholan-22-al produces 3-keto-11 β -hydroxybisnor-17(20)-cholen-22-al.

(d) 3 α -acetoxybisnor-20-bromo-5-cholen-22-al produces 3 α -acetoxybisnor-5,17(20)-choladien-22-al.

(e) 3 α -hydroxybisnor-20-bromo-5-cholen-22-al produces 3 α -hydroxybisnor-5,17(20)-choladien-22-al.

(f) 3 α -acetoxybisnor-6-nitro-20-bromo-5-cholen-22-al produces 3 α -acetoxy-6-nitrobisnor-5,17(20)-choladien-22-al.

(g) 3-ketobisnor-9(11)-oxido-20-bromo-5,7-choladien-22-al produces 3-ketobisnor-9(11)-oxido-5,8-maleic anhydride adduct.

(h) 3,6,11-triketobisnor-20-bromo-4-cholen-22-al produces 3,6,11-triketobisnor-4,17(20)-choladien-22-al.

EXAMPLE 21

In the same manner as given in Example 3, ozonizing:

(a) 3-ketobisnor-11 α -hydroxy-17(20)-cholen-22-al produces 11 α -hydroxyetiocholane-3,17-dione.

(b) 3-ketobisnor-11 α -acetoxy-17(20)-cholen-22-al produces 11 α -acetoxyetiocholane-3,17-dione.

(c) 3-ketobisnor-11 β -hydroxy-17(20)-cholen-22-al produces 11 β -hydroxyetiocholane-3,17-dione.

(d) 3 α -acetoxybisnor-5,17(20)-choladien-22-al produces 3 α -acetoxy-5-androsten-17-one (dehydroandrosterone acetate).

(e) 3 α -hydroxybisnor-5,17(20)-choladien-22-al produces 3 α -hydroxy-5-androsten-17-one (dehydroandrosterone).

(f) 3 α -acetoxybisnor-6-nitro-5,17(20)-choladien-22-al produces 3 α -acetoxy-6-nitro-5-androsten-17-one.

(g) 3-ketobisnor-9(11)-oxido-5,8-maleic anhydride adduct produces 9(11)-oxido-5,7-androstadiene-3,17-dione 5,8-maleic anhydride adduct.

(h) 3,6,11-triketobisnor-4,17(20)-choladien-22-al produces 4-androstene-3,6,11,17-tetraone.

It is to be understood that the invention is not to be limited to the exact details of operation or exact compounds shown and described, as obvious modifications and equivalents will be apparent to one skilled in the art, and the invention is therefore to be limited only by the scope of the appended claims.

60 I claim:

1. A 20-halobisnorcholane-22-al selected from the group consisting of 3-ketobisnor-20-halo-4-cholen-22-al; 3-ketobisnor-20-halocholan-22-al; 3-ketoallobisnor-20-halocholan-22-al, 3-hydroxybisnor-20-halocholan-22-al and 3-acetyl-oxobisnor-20-halocholan-22-al; 3-hydroxyallobisnor-20-halocholan-22-al and 3-acyloxyallobisnor-20-halocholan-22-al; 3-hydroxybisnor-20-halo-5-cholen-22-al; 3,11-diketobisnor-20-halo-4-cholen-22-al, 3-ketobisnor-11 α -hydroxy-20-halo-4-cholen-22-al, 3-ketobisnor-11 β -hydroxy-20-halo-4-cholen-22-al and 3,6-diketobisnor-20-halocholan-22-al, wherein the halogen atom has an atomic weight of 34 to 81, inclusive, and wherein the acyl group is of an organic carboxylic acid containing from one to eight carbon atoms, inclusive.

2. 3-ketobisnor-20-bromo-4-cholen-22-al.
 3. 3,11-diketobisnor-20-bromo-4-cholen-22-al.
 4. 3 α -acetoxybisnor-20-bromocholan-22-al.
 5. 3-oxygenated-17(20)-bisnorcholesterol-22-al.
 6. 3-ketobisnor-4,17(20)-choladien-22-al.
 7. 3,11-diketobisnor-4,17(20)-choladien-22-al.
 8. A process for the production of a 20-halobisnor-cholan-22-al which comprises: treating a 22-(N-tertiaryamino)-bisnor-20(22)-cholene selected from the group consisting of 22-(N-tertiaryamino)-bisnor-4,20(22)-choladien - 3 - ones, 22 - (N - tertiaryamino) - bisnor-20(22)-cholen-3-one, 22-(N-tertiaryamino)-allobisnor-20(22)-cholen-3-one, 3-hydroxy- and 3-acyloxy-22-(N-tertiaryamino)-bisnor-20(22)-cholenes, 3-hydroxy- and 3 - acyloxy - 22 - (N - tertiaryamino) - allobisnor-20(22)-cholen-3-one, 3-hydroxy- and 3-acyloxy-22-(N-tertiaryamino) - bisnor - 5,20(22) - choladien, 22-(N-tertiaryamino) - bisnor - 4,20(22) - choladien - 3,11 - dione, 22-(N-tertiaryamino)-bisnor-20(22)-cholen-3,6-dione, wherein the acyl group is of an organic carboxylic acid having from one to eight carbon atoms and wherein the tertiaryamino radical is of the formula:

in which n and n' are whole numbers from one to two, inclusive, with halogen of atomic weight 34 through 81, inclusive, at a temperature between about minus thirty and about plus twenty degrees centigrade to obtain the corresponding 20-halobisnor-cholan-22-al.

9. A process for the production of 3-ketobisnor-20-bromo-4-cholen-22-al which comprises: treating 22-(N-piperidyl)-bisnor-4,20(22)-choladien-3-one with bromine, dissolved in an organic solvent, at a temperature between minus thirty and about plus twenty degrees centigrade to obtain 3-ketobisnor-20-bromo-4-cholen-22-al.

10. A process for the production of 3,11-diketobisnor-20-bromo-4-cholen-22-al which comprises: treating 22-(N-piperidyl)-bisnor-4,20(22)-choladien-3-one with bromine, dissolved in an organic solvent, at a temperature between minus thirty and about plus twenty degrees centigrade to obtain 3,11 - diketobisnor - 20 - bromo-4-cholen-22-al.

11. A process for the production of 3 α -acetoxybisnor-20-bromocholan-22-al which comprises treating 3 α -acetoxy-22-(N-piperidyl)-bisnor-20(22)-cholen with bromine at a temperature between minus thirty and about plus twenty degrees centigrade to obtain 3 α -acetoxybisnor-20-bromocholan-22-al.

12. A process for the preparation of a 3-oxygenated-17(20)-bisnorcholesterol-22-al which comprises: treating a 3-oxygenated 22-(N-tertiaryamino)-bisnor-20(22)-cholene wherein the tertiaryamino radical is of the formula:

in which n and n' are whole numbers from one to two, inclusive, with halogen of atomic weight 34 through 81, inclusive, between about minus thirty and about plus twenty degrees centigrade to obtain the corresponding 3-oxygenated 20-halobisnorcholesterol-22-al and dehydrohalogenating the 3-oxygenated 20-halobisnorcholesterol-22-al through heating with a tertiary amine to obtain the corresponding 3-oxygenated-17(20)-bisnorcholesterol-22-al.

13. A process for the preparation of a 3-oxygenated-17(20)-bisnor-cholen-22-al which comprises: treating a 3-oxygenated 22-(N-tertiaryamino)-bisnor-20(22)-cholen wherein the tertiaryamino radical is

in which n and n' are whole numbers from one to two, inclusive, with bromine in an organic solvent between about minus thirty and about plus twenty degrees centigrade to obtain the corresponding 3-oxygenated-20-bromobisnorcholesterol-22-al and dehydrohalogenating the thus obtained 3-oxygenated-20-bromobisnorcholesterol-22-al with pyridine at a temperature between about sixty and about 100 degrees centigrade to obtain the corresponding 3-oxygenated-17(20)-bisnorcholesterol-22-al.

14. A process for the preparation of 3-ketobisnor-4,17(20)-choladien-22-al which comprises: treating a 22-(N - tertiaryamino) - bisnor - 4,20(22) - choladien - 3 - one wherein the tertiaryamino group is

in which n and n' are whole numbers from one to two inclusive with halogen of atomic weight 34 through 81, inclusive, between about minus thirty and about plus twenty degrees centigrade to obtain the corresponding 3-ketobisnor-20-halo-4-cholen-22-al and dehydrohalogenating the thus obtained 3-ketobisnor-20-halo-4-cholen-22-al thru heating with a tertiary amine to obtain 3-ketobisnor-4,17(20)-choladien-22-al.

15. A process for the preparation of 3-ketobisnor-4,17(20)-choladien-22-al which comprises: treating 22-(N-piperidyl)-bisnor-4,20(22)-choladien-3-one with bromine in an organic solvent at a temperature between

30 about minus thirty and about plus twenty degrees to obtain 3-ketobisnor-20-bromo-4-cholen-22-al and dehydrobrominating the thus obtained 3-ketobisnor-20-bromo-4-cholen-22-al with pyridine at a temperature of about sixty to about 100 degrees centigrade to obtain 3-ketobisnor-4,17(20)-choladien-22-al.

16. A process for the preparation of 3,11-diketobisnor-4,17(20)-choladien-22-al which comprises: treating a 22-(N-tertiaryamino)-bisnor-4,20(22)-choladien-3,11 - dione wherein the tertiaryamino group is

in which n and n' are whole numbers from one to two, inclusive with halogen of atomic weight 34 through 81, inclusive, between about minus thirty and about plus twenty degrees centigrade to obtain the corresponding 3,11 - diketobisnor-20-halo-4-cholen-22-al and dehydrohalogenating the thus obtained 3,11-diketobisnor-20-halo-4-cholen-22-al by heating with a tertiary amine to obtain 3,11-diketobisnor-4,17(20)-choladien-22-al.

17. A process for the preparation of 3,11-diketobisnor-4,17(20)-choladien-22-al which comprises: treating 22-(N-piperidyl)-bisnor-4,20(22)-choladiene-3,11-dione with bromine in an organic solvent at a temperature between about minus thirty and about plus twenty degrees centigrade to obtain 3,11-diketobisnor-20-bromo-4-cholen-22-al and dehydrobrominating the thus obtained 3,11-diketobisnor-20-bromo-4-cholen-22-al with pyridine at a temperature between about sixty and about 100 degrees centigrade to obtain 3,11-diketo-bisnor-4,17(20)-choladien-22-al.

18. A process for the production of compounds selected from the group consisting of 3-oxygenated 17-ketosteroids of the androstane and etiocholane series, which comprises: treating a 3-oxygenated 22-(N-tertiaryamino)-bisnor-20(22)-cholene wherein the tertiaryamino radical is

in which n and n' are whole numbers from one to two, inclusive, with halogen of atomic weight 34 through 81, inclusive, between about minus thirty and about plus

twenty degrees centigrade to obtain the corresponding 3 - oxygenated 20-halobisnorcholan-22-al, dehydrohalogenating the 3 - oxygenated 20 - halobisnorcholen-22-al through heating with a tertiary amine to obtain the corresponding 3-oxygenated-17(20)-bisnorcholan-22-al and ozonolyzing the thus obtained 3-oxygenated-17(20)bisnorcholan-22-al to obtain the corresponding 3-oxygenated 17-ketosteroid.

19. A process for the production of compounds selected from the group consisting of 3-oxygenated 17-ketosteroids of the androstane and etiocholane series, which comprises: treating a 3-oxygenated 22-(N-tertiaryamino)-bisnor-20(22)-cholene wherein the tertiaryamino radical is

in which n and n' are whole numbers from one to two, inclusive, with bromine in an organic solvent between about minus thirty and about plus twenty degrees centigrade to obtain the corresponding 3-oxygenated 20-bromobisnorcholan-22-al, dehydrobrominating the 3-oxygenated 20-bromobisnorcholen-22-al at a temperature between about sixty and about 100 degrees centigrade with pyridine to obtain the corresponding 3-oxygenated bisnor-17(20)-cholen-22-al and ozonolyzing the thus obtained 3-oxygenated bisnor-17(20)-cholen-22-al to obtain the corresponding 3-oxygenated 17-ketosteroid.

25

20. A process for the production of 4-androstene-3,17-dione which comprises: treating 22-(N-piperidyl)-bisnor-4,20(22)-choladien-3-one with bromine in an organic solvent at a temperature between about minus thirty and about plus twenty degrees centigrade to obtain 3-ketobisnor-20-bromo-4-cholen-22-al, dehydrobrominating the thus obtained 3-ketobisnor-20-bromo-4-cholen-22-al with pyridine at a temperature between about sixty and about 100 degrees centigrade to obtain 3-ketobisnor-4,17(20)-choladien-22-al and ozonolyzing the thus produced 3-ketobisnor-4,17(20)-choladien-22-al to obtain 4-androstene-3,17-dione.

21. A process for the production of adrenosterone which comprises: treating 22-(N-piperidyl)-bisnor-4,20-(22)-choladien-3,11-dione with bromine in an organic solvent at a temperature between about minus thirty and about plus twenty degrees centigrade to obtain 3,11-diketobisnor-20-bromo-4-cholen-22-al, dehydrobrominating the thus obtained 3,11-diketobisnor-20-bromo-4-cholen-22-al with pyridine at a temperature between about sixty and about 100 degrees centigrade to obtain 3,11-diketobisnor-4,17(20)-choladien-22-al, and ozonolyzing the thus produced 3,11-diketobisnor-4,17(20)-choladien-22-al to obtain adrenosterone.

UNITED STATES PATENT OFFICE
Certificate of Correction

Patent No. 2,844,605

July 22, 1958

Raymond L. Pederson

It is hereby certified that error appears in the printed specification of the above numbered patent requiring correction and that the said Letters Patent should read as corrected below.

Column 3, lines 23 to 26, the formula should appear as shown below instead of as in the patent—

same column 3, line 52, for “-homomorpholinyl” read — -homomorpholinyl—; column 5, line 34, for “(tetrahydroisoquinoline)” read —(tetrahydroisoquinolino)—; line 59, for “dissolved” read —dissolved—; line 67, for “percent” read —percent—; column 6, line 61, for “-choladine-” read — -choladiene—; column 10, line 3, for “cyclopentylpropionyloxy” read —cyclopentylpropionyloxy—; line 14, for “-nitrobenzenesulfonyloxy” read — -nitrobenzenesulfonyloxy—; column 12, line 56, for “-chloadien-” read — -choladien—; column 13, line 64, for “-choladine” read — -choladiene—; column 14, line 61, for “seleced” read —selected—.

Signed and sealed this 7th day of July 1959.
